UNITED STATES PATENT OFFICE.

CHARLES H. KNAPP, OF PATERSON, NEW JERSEY.

MACHINE FOR FOLDING CLOTH BLANKS.

SPECIFICATION forming part of Letters Patent No. 699,192, dated May 6, 1902.

Application filed January 17, 1902. Serial No. 90,105. (No model.)

To all whom it may concern:

Be it known that I, CHARLES H. KNAPP, a citizen of the United States, residing in Paterson, in the county of Passaic and State of New Jersey, have invented certain new and useful Improvements in Machines for Folding Wristbands; and I do hereby declare the following to be a full, clear, and exact description of the invention, such as will enable others skilled in the art to which it appertains to make and use the same, reference being had to the accompanying drawings, and to letters and figures of reference marked thereon, which form a part of this specification.

This invention relates to machines for folding collars, cuffs, wristbands, and other similar articles; and it consists in an improved construction of the machine of this nature patented to me by United States Letters Patent No. 668,920, February 26, 1901.

My improved machine is designed principally for folding wristbands having rounded corners, but may be used for folding other articles, such as those above mentioned, of substantially similar shape without altering the construction or general principles of operation materially.

The invention will be found fully illustrated in the accompanying drawings, wherein—

Figure 1 is a side view of my improved machine. Fig. 2 is a top plan view thereof, slightly enlarged. Fig. 3 is a view in front elevation of the die. Fig. 4 is a top plan view of the die proper—*i. e.*, of the die with its operating mechanism removed. Fig. 5 is a top plan view of said die proper contracted, with the sliding plates for actuating the die-plates removed. Figs. 6 and 7 illustrate a pair of the die-plates, Fig. 6 being a plan view and Fig. 7 a sectional view on the line *xx* in Fig. 6; and Fig. 8 is a perspective view of a certain latch.

a is the framework of the machine, and *b* the bed, the latter surmounting the framework and being provided on its under side with the usual centrally-disposed heat chest or chamber *c*, adapted to be connected by pipes *d* with a steam or other generator of a heat-carrying medium.

On the top of the bed *b* is arranged at the front middle portion thereof a folding-plate *e*, and at the back thereof two other folding-

plates *f*, one of which has its top surface recessed, as at *g*, for the reception of a coincident guiding lug or projection *h* on the other folding-plate *f*. The plate *e* has pairs of guide-slots *i*, arranged parallel with the sides of the bed *b*, while each of the folding-plates *f* has similar guide-slots *j*, said slots *j* of the plates *f* being disposed in reversely oblique directions. (See Fig. 2.) The outermost slots of the several plates are penetrated by guiding-bolts *k*, projecting up from the bed *b*, while their innermost slots are penetrated by bolts *l*, which project down through the bed and are free to move vertically only. The lower ends of these last-mentioned bolts are connected by links *m*, the several links being adapted to sustain a claw *n*. To the claw is centrally connected a vertical shaft *o*, whose lower end is in turn connected with a depressing mechanism consisting of a lever *p* and a treadle *q*, fulcrumed in the frame, and a connecting-link *r*. The arrangement is such that by depressing the treadle *q* the inner edge portions of the several folding-plates will exert pressure on the bed *b* or an article disposed between them and said bed. A spiral spring *s*, connecting the treadle *q* with the frame, normally maintains the treadle raised, and consequently keeps the pressure off the folding-plates.

t designates three shafts which are journaled on the under side of the bed *b* and are connected by intermeshing bevel-gears *u*, which they carry. The shaft *t*, which is adjacent the front of the machine, carries at one end a crank *v*, from which the series of shafts is actuated. At either of its two limits of motion this crank takes against a spiral spring-buffer *w*, carried in a socket *x*, formed on a bracket *y*, projecting from the framework *a*, which bracket being secured to the framework by a slot-and-bolt connection *z* is thus made vertically adjustable. The front and rear shafts *t* carry cams *1*, received by forked projections *2*, secured to the folding-plates *f* by screws *3*, and extending downwardly through openings *4* in the bed. Thus by operating the crank the folding-plates *f* may be moved inwardly or outwardly on the bed *b*. It should be remarked that the front folding-plate *e* and the left-hand rear folding-plate *f* have devices *5*, connecting

them with their neighboring plates to the right in the manner and for the purposes fully set forth in my patent aforementioned. 6 is an arm which is fulcrumed at 7 at the back of the bed b, and whose free end is formed with a head 8, having an integral cross-piece 9. To the ends of the cross-piece 9 are rigidly secured by nuts 10 the studs 11 of a guide-plate 12. This guide-plate is provided with relatively reverse series of oblique slots 13, the slots of the series being preferably alined and alternating with each other, as shown in Fig. 5. In these slots work the rigid upwardly-extending pintles 14 of the contractile die-plates 15. The upper ends of these pintles are received by cross-slots 16 in actuating-plates 17, which move in a groove 17' in the guide-plate 12 and have longitudinal slots 18, receiving the studs 11 and permitting an inward and outward rectilineal movement of said actuating-plates. The tops of the pintles carry screws 19, whose heads keep the several parts in place. The actuating-plates 17 carry at their inner ends other pintles 20, which work in eccentric slots 20' in a disk 21, carried by a shaft 22, which is journaled in the head 8 of the arm 6, and is adapted to be turned by a handle 23.

In folding narrow articles, such as wristbands, it is necessary that the die-plates should be contracted into a very small compass. For this reason, and as best shown in Fig. 6, I cut away practically all of each die-plate except the edge portion thereof and two or more inwardly-projecting tabs or ears 24. The tabs or ears on the opposed die-plates are arranged out of coincidence with each other so as not to interfere, and in order to bring the inner edges of the two plates referred to into the closest proximity said tabs or ears are elevated so as to overlap the opposite die-plate. Said tabs or ears carry the pintles 14. The meeting edges of the several die-plates, it should be remarked, overlap each other even in their most expanded position, (the two die-plates shown in Fig. 6 being abnormally separated.) It should also be remarked that the die-plates are shaped so as to together correspond substantially to the outline of the article which is to be folded.

The arm 6 has an integral rearward extension 25, having a detachable bracket 26, which forms therewith a guide or runway 27 for the rollers 28 of a traveler 29, said traveler being connected with a crank 30, formed integrally with the handle 23 by a pitman 31, pivotally secured at its ends to these parts. The traveller is connected with the framework a by a spiral spring 32.

33 is a hook, which is also formed integrally with the arm 6 and is adapted to engage a latch or detent 34, pivoted in the bed b and normally resting in a substantially horizontal position therein when the arm 6 and the parts it carries assume the position shown in dotted lines in Fig. 1. A tappet 35 on the rear shaft t is adapted to engage a lug 36, ex-

tending from the latch, so as to elevate said latch and so release the hook 33. When the arm 6 and the parts it carries are thrown into the position shown in dotted lines in Fig. 1, a spiral spring 37, carried by the hook 33 and adapted to engage the bed b, serves as a stop or buffer.

38 represents gages each having flanges 75, 39, arranged at right angles to each other, each gage being secured on a corresponding folding-plate f by a slot-and-pin connection 40, which permits an adjustment of the gage in the direction of movement of said plate. The operator sets his work in position for folding by these gages.

In operation the material to be folded is laid on the bed b with its edges slightly overlapping the folding-plates e and f. At this time, of course, the folding-plates are retracted—i. e., in their outermost positions—and the die and its accessory parts thrown into the dotted-line position illustrated in Fig. 1. The die expanded is then lowered until it rests on the material. It should be remarked that so long as the folding-plates are retracted to their full extent the die can be lowered to rest on the bed b, though expanded to its full extent. The crank v is then thrown over into the position shown in dotted lines in Fig. 2, causing the folding-plates e and f to move inwardly. This operation effects the folding of the edge portions of the material around the edges of the die-plates, and it should be remarked that preferably and by a proper arrangement of the cams 1 the folding-plates may be made to move inwardly in a successive or substantially successive movement. The operator then draws the handle 23 toward him, causing the disk 21 to revolve and through it and its connections with the die-plates the contraction of said die-plates. When the die-plates have been withdrawn to their full extent, the die may be elevated from the material, whereupon the operator may, by pressing down on treadle q, apply the pressure to the folding-plates necessary to properly crease the material where folded. While the folding-plates are in their innermost position it is desired that the arm 6 carrying the die (which is at this time in dotted-line position illustrated in Fig. 1) should be positively locked back. Otherwise an inexperienced or careless operator might accidentally permit the die to fall, causing the edges of the die-plates and folding-plates to strike against and damage each other. Therefore when the die is thrown back at the point in the operation above referred to the hook 33 engages the latch 34 and so keeps the arm and die elevated, and these parts cannot again be returned to the lowered position until, in retracting the folding-plates f, the lug 5 has caused the latch 34 to release the hook.

The traveler 29 is of value as a counterbalance for the die, which latter may be thus raised and lowered by the operator with great

facility. The peculiar connection between this traveler and the handle 23 is a very practical and convenient factor in the operation of the parts involved. The spring 32 not only acts with a counterbalancing effect on the die, but tends to keep it open ready for the next folding operation whenever the die is lowered.

It is to be understood that where the terms "support" and "movable support" are used hereinafter in some of the claims the bed *b* and the arm 6 of that embodiment of my invention which is shown in the accompanying drawings are intended to be respectively comprehend.

Having thus fully described my invention, what I claim as new, and desire to secure by Letters Patent, is—

1. In a folding or other substantially similar machine, the combination, with a support, of another and movable support, coacting forming means, a part of said means being mounted on said first-named support and the rest on the movable support, and means, controlled from the portion of said forming means on said first-named support, for locking the movable support in a retracted position, substantially as described.

2. In a folding or other substantially similar machine, the combination, with a support, of another and movable support, coacting forming devices, a part of said devices being mounted on said first-named support and the rest on the movable support, means for actuating the forming devices on said first-named support, and means, controlled from said actuating means, for locking said movable support in a retracted position, substantially as described.

3. In a folding or other substantially similar machine, the combination, with a support, of another and fulcrumed support, coacting forming devices, a part of said devices being mounted on said first-named support and the rest on the fulcrumed support, means for actuating the forming devices on said first-named support, a hook on said fulcrumed support, and a movable locking-detent adapted to engage said hook, said detent being controlled from said actuating means, substantially as described.

4. In a folding or other substantially similar machine, the combination, with a bed, of a fulcrumed support, movable folding-plates mounted on said bed, a contractile die carried by said support and adapted to coact with said folding-plates, means for actuating said folding-plates, a tappet movable with a part of said actuating means, and a movable detent, said detent being adapted to engage said support in its elevated position and said tappet being adapted to move said detent out of operative position when said folding-plates are retracted, substantially as described.

5. In a folding or other similar machine, the combination of a fulcrumed arm, a tool carried by said arm and comprising a movable

part, a guide projecting from the fulcrum of said arm, a counterbalancing traveler arranged to move on said guide, and operative connecting means between the traveler and the movable part of said tool, substantially as described.

6. In a folding or other similar machine, the combination of a fulcrumed arm, a tool carried by said arm, a rotary handle for said tool, a guide projecting from the fulcrum of said arm, a counterbalancing traveler arranged to move on said guide, and operative connecting means between said traveler and the handle, substantially as described.

7. In a folding or other similar machine, the combination of a fulcrumed arm, a contractile die carried by said arm, a rotary handle for said contractile die, a guide projecting from the fulcrum of said arm, a counterbalancing traveler arranged to move on said guide, operative connecting means between said traveler and the handle, and a spring controlling said traveler, substantially as described.

8. In a folding or other similar machine, the combination of a fulcrumed arm having a guide, a movable part carried by said arm, means, comprising another movable part arranged on said guide, for turning said arm on its fulcrum; and operative connecting means between said parts, substantially as described.

9. In a folding or other similar machine, the combination of a fulcrumed arm, a movable part carried by said arm, a guide projecting from the fulcrum of said arm, a movable counterbalancing device arranged on the guide, and operative connecting means between said movable part and said counterbalancing device, substantially as described.

10. In a contractile die, the combination of die-plates arranged to move in a common plane into close proximity to each other and having projections extending from each of said plates toward the other, the projections of each plate being arranged out of the plane, and out of opposition to the projections of the other plate, and a slotted guiding part receiving said projections, substantially as described.

11. In a contractile die, the combination of die-plates arranged to move in a common plane and into close proximity to each other, the adjoining portions of said plates being cut away to form alternating spaces and projections, and the projections of each plate being arranged out of the plane, and opposed to the spaces, of the other plate, and a slotted guiding part receiving said projections, substantially as described.

12. In a contractile die, the combination of die-plates arranged to move in a common plane and into close proximity to each other, the adjoining portions of said plates being cut away to form alternating spaces and projections, and the projections of each plate being arranged out of the plane, and opposed to the spaces, of the other plate, a slotted guiding

part receiving said projections, a support carrying said guiding part, and sliding plates engaging the projections of and adapted to actuate said die-plates and guided in said 5 guide-plates, substantially as described.

13. In a contractile die, the combination of die-plates arranged to move in a common plane into close proximity to each other and having projections extending from each of 10 said plates toward the other, the projections of each plate being arranged out of the plane,

and out of opposition to the projections, of the other plate, and means, engaging said projections, for guiding said plates, substantially as described.

In testimony that I claim the foregoing I have hereunto set my hand this 14th day of January, 1902.

CHARLES H. KNAPP.
